UNITED STATES PATENT OFFICE

FRANK D. HOLMES AND WALTER H. TRICK, OF DETROIT, MICHIGAN.

KNITTING-MACHINE

1,388,341.

Specification of Letters Patent. Patented Aug. 23, 1921.

Application filed August 2, 1919. Serial No. 314,944.

To all whom it may concern:

Be it known that we, FRANK D. HOLMES and WALTER H. TRICK, citizens of the United States, and residing at Detroit, county of Wayne, and State of Michigan, have invented a new and Improved Knitting-Machine, of which the following is a specification.

This invention relates to the construction of knitting machines adapted to form fabrics from two separate yarns which are knitted into the fabric simultaneously and from one of which loops are formed on the interior surface of the fabric to increase the thickness and warmth thereof. The principal object of this invention is to provide a knitting machine which will produce a "two-yarn" fabric provided with comparatively short loops formed from one of the 20 yards which will practically lie directly over the corresponding portion of the other yarn and cover it on both sides of the fabric.

This invention consists in a series of novel sinkers for forming the loops on the interior 25 of the fabric and in the novel cam mechanism for positioning the sinkers. It also consists in the details of construction illustrated in the accompanying drawings and particularly pointed out in the claim.

30 In the accompanying drawings, Figure 1 is a plan of this improved knitting machine. Fig. 2 is a section on the line 2—2 of Fig. 1. Fig. 2^a is a similar section of a portion of the structure shown in Fig. 2 on a plane 35 passing through a needle. Fig. 3 is a portion of the cam plate seen from below. Fig. 4 is a section on the line 4—4 of Fig. 2. Fig. 5 is a perspective on a large scale of a knitting needle. Fig. 6 is a diagram showing 40 the method of producing the loops. Figs. 7 to 12 inclusive are views showing the action of the sinkers and needles.

The needle cylinder 1 of this machine connects to the skeleton cylinder or needle 45 guide and is rotated by the bevel-gear ring 3 at the lower end of this skeleton cylinder through the medium of the pinion 4. This needle guide consists of a lower ring 3 and upwardly extending fingers 6 which are 50 connected at their upper ends by means of a slotted ring 2. The needles 7, particularly shown in Fig. 5, have butts 8 which extend between the guide fingers 6.

A stationary cam 9 has a groove or needle race 10 into which the butts 8 of the needles 55 extend and as the needle cylinder revolves, the needles are lowered and then elevated. The upper end of each needle is in the form of a hook 12 and each has a groove 13 in which the latch 14 is pivoted. The needle cylinder has rings 15, interrupted by the vertical grooves that receive the needles and between these rings are the coil springs 16 that hold the needles in their grooves.

Supported above the needle cylinder is a 65 stationary latch ring 18 having a guide hole 19 and guide tube 20 for the yarns 22 and 23, one of which primarily gives strength to the fabric and the other warmth. The latch ring prevents the latches 14 from flying out. In many cases the yarn 23 is of cotton and the yarn 22 of wool. Fitted into the upper end of the needle cylinder is a throat ring 24 which is made separate from the needle cylinder for manufacturing reasons. 70 The parts thus far described are old and well known.

The needle cylinder and throat ring are formed with radial grooves and holes to receive the sinkers 26 which have the butts 27 80 to engage the cam ring described later on, the tufting points 28, the supporting fingers 29 and the guides 30 that fit in slots in the top end of the needle cylinder and project beneath a portion of the throat ring. 85 Mounted on the needle cylinder is a sinker ring 32 having radial slots in which the butts of the sinkers are slidable.

Above the sinker ring and supported thereby is a sinker-cam ring 33 which is stationary and which so operates the sinkers that the fabric is formed with loops of the yarn 22 on the inside. The outside of the fabric is plaited-knitted and the two yarns are so positioned that the yarn 22 is always 90 over the yarn 23. The bottom side of the sinker-cam ring is shown in Fig. 3.

During practically three-fourths of the period during which the needle cylinder makes one complete rotation, the needles are 100 elevated and the sinkers are in their normal position. During the seventh one-eighth of the turn, the sinkers are pulled back so that the tufting points may avoid the yarn guide 20, as shown in Fig. 2. During the last 105 eighth of the turn the needles are pulled down

to form loops and then pushed up and the sinkers are pushed in to support the yarn 23 and then to press inwardly against the finished fabric while the needle moves upward in the just finished loop.

Referring to Fig. 3, the sinker-cam ring 33 has a circular groove 37 to receive the butts 27 of the sinkers and extending about three-fourths of the circumference of the 10 ring up to the point 38. From this point to the point 39 the continuation of this groove might be straight except that the present machine may be used for knitting heels on socks in which case the needle cylinder reciprocates through about forty-five degrees and the cam groove between the points 38 and 39 is utilized. When the butts reach the circular portion 40, the sinkers are so far back that the tufting points 28 will pass 15 outside of the yarn tube 20, as shown in Fig. 2.

As the needle cylinder rotates, the yarn 23 will be laid on top of the supporting fingers 29 of the sinkers. The inclined part 42 of the cam groove moves the sinkers inwardly to bring the tufting points 28 below the yarn 22 as it leaves the hole 19 so that the yarn 22 will be laid on these points. When the butt of a sinker reaches the middle 25 of the part 40 of the groove, the needle next behind it begins to move down and the hook of the needle reaches the yarn 22 just as the yarn 22 is laid on the tufting point in front of it. This is the location of the sinker *a* 30 in Fig. 6, and this sinker will be at about the inner end of the portion 42 of the cam and indicated by line *a* in Fig. 3. As the needle cylinder turns, the needle keeps on going down and just as the butt of the sinker 35 reaches the line *b* in Fig. 3, the needle will reach the lower yarn 23, as indicated in Fig. 6, and then begin to draw the two yarns through the stitch A already on the needle, the positions of the needle, the sinker, the 40 stitch and the yarns for the positions *a* and *c* being shown in Figs. 8 and 9 respectively. The latter shows the yarn 22 lying on top of the tufting finger and the beginning of the formation of the loop. 45

50 The sinker then moves inwardly, its positions being indicated by the lines *d* to *h* inclusive in Fig. 3, and the positions of the needle being indicated in Fig. 6. At the time the needle has been lifted so far that 55 the top of the hook is almost in contact with the previous stitch A, as shown in Fig. 10, the sinker is at the line *h* in Fig. 3 and is just pushing the fabric inward so as to move the stitch A out of the path of the back of 60 the needle, the loop remaining over the tufting finger. If the top of the hook should press upward against the stitch A, it is 65 liable to tear or break it. The needle cylinder continues to turn and the needle to rise and soon passes to the positions shown in

Figs. 11 and 12, the latter being the position held during the passage of the sinker butt through the long part 37 of the cam ring.

Until the sinker has reached the position indicated by the line *h* in Fig. 6, the loop of the yarn 22 is held by the tufting point 28, but because of the upward movement of the needle and the pull of the knitted fabric, the loop of the yarn 22 begins to slip and as the sinker jumps back after it passes the line *h*, the loop of the yarn 22 is cast off shortly after it passes the line *i*. The inward movement of the following sinkers tends to pull down or shorten this loop of the yarn 22 until it is hardly more than a loose stitch.

The invention therefore consists in so proportioning the sinkers and the cam groove that the tufting points will always be moved under the yarn 22 in time to support it before the yarn is engaged by the hooks of the needles, and continue to support the loops which are thus formed so long as there is any pull on the yarns and thus prevent the loops from being pulled down. The length of the loops will be determined by the height of the tufting fingers, and in practice we have determined that we can make them from one-sixteenth to three-eighths of an inch long. We prefer however to make them quite short, no longer in fact than is necessary to give sufficient length to permit them to lie loosely over the yarns 23 just below them. It has been impossible to make these short loops heretofore and the new fabric with the yarns 22 of heavy wool made into loops which lie flat over the cotton yarns 23 on the inside of the sock has made possible a garment of unusual strength and warmth. At the same time the short loops make for a moderately thin fabric instead of the excessively thick material which results when the loops are long. The cam ring 33 can of course be made all in one piece, but as the groove loses its exact shape because of wear, we prefer to form the parts 44 and 45 separate and adjustably secure them to the cam ring by means of bolts 47 that extend through the slots 48 and 49. The part 46 may also be made separate so that it can be replaced if worn.

In this machine as in all others plaited-knitting machines of the same general construction using two yarns which enter one above the other, the upper yarn gets to the outside of the fabric during the knitting operations and covers the lower yarn. But unlike the other machines of this construction, the lower yarn does not lie over the upper yarn on the inside of the fabric, this being prevented by the forming of the loops. The tufting points hold up the upper yarn while the lower yarn is drawn tight and finally cast off this upper yarn so that the loops may fall over the lower yarn.

If plain work is desired, the cams are so timed that both yarns will fall on the supporting fingers 29, no loops being possible under such conditions. When plain plaited work is desired the cams 45 may be separated, the screws 47 being slackened up to permit this movement.

We claim:—

In a knitting machine, a needle cylinder having radial and longitudinal guide grooves, needles mounted in the longitudinal grooves and means for moving said needles up and down, sinkers mounted in the radial grooves and having supporting fingers, tufting points and butts, a sinker cam-ring to move the sinkers in and out, means for guiding a pair of yarns to the sinkers so that one yarn will lie on the other below the tufting

points, means to turn the needle cylinder relative to the sinker cam-ring, and means to move the needles down to engage both yarns and pull them through the previous stitch, said sinker cam-ring being formed to hold the tufting points between said yarns until just before the needle in its upward movement passes back of the previously formed stitch and then to move the sinkers back to release the yarn supported thereby so that the pressure of the succeeding sinkers will draw down the loop which has previously been supported by said sinker until it substantially contacts with and covers the other yarn.

FRANK D. HOLMES.
WALTER H. TRICK.
